[57] CLAIM

The ornamental design for a golf club head, substantially as shown and described.

DESCRIPTION

FIG. 1 is a perspective view of a golf club head showing my new design; FIG. 1 is shown fragmentally for convenience of illustration;

FIG. 2 is a side elevational view showing the face;

FIG. 3 is an outer end elevational view;

FIG. 4 is a top plan view;

FIG. 5 is a bottom plan view; and

FIG. 6 is an inner end elevational view.
